UNITED STATES PATENT OFFICE.

GEORGE VASSAR, JR., OF NEW YORK, N. Y.

RAILROAD-GATE.

SPECIFICATION forming part of Letters Patent No. 406,551, dated July 9, 1889.

Application filed January 23, 1889. Serial No. 297,245. (No model.)

To all whom it may concern:

Be it known that I, GEORGE VASSAR, Jr., of New York, in the county and State of New York, have invented a certain new and useful 5 Improvement in Railroad Gates, of which the following is a specification.

My improvement relates to gates which are used in connection with railroads at crossings.

The object of the improvement is to provide a mechanism whereby said gates can be slowly raised and lowered through an impulse produced by the passage of a train or car over a tappet.

I will describe in detail a gate and actuating mechanism embodying my improvement, and then point out the novel features in my claims.

In the accompanying drawings, Figure 1 is a plan of a railway furnished with gates and mechanism embodying my improvement. Fig. 2 is a side elevation of the same. Fig. 3 is a side view, on a larger scale, of one of the gates and part of the actuating mechanism. Fig. 4 is an edge view of the parts shown in Fig. 3. Fig. 5 is a longitudinal section of a box forming part of my improvement. Fig. 6 is a transverse section of the same.

Similar letters of reference designate corresponding parts in all the figures.

30 A' A² designate two railway-tracks extending side by side in the ordinary manner. Trains are intended to run upon these tracks in reverse directions, as indicated by the arrows marked upon the tracks.

35 B' B² designate gates, (shown as consisting of swinging arms secured to standards B,) arranged one adjacent to the outer side of the track A', and the other adjacent to the outer side of the track A². These gates B' B² are intended to operate in unison and to be actuated by a train passing along the track A'.

40 C' C² designate similar gates pivoted or fulcrumed to standards C, arranged in positions like those occupied by the standards B. These 45 gates C' C² are intended to operate in unison and to be actuated by trains passing over the track A².

It will be seen that the gates B' B² are opposite the gates C' C². The pair of gates B' 50 B² are not, however, to extend over the cross-

ing D when the gates C' C² are lowered. Neither are the gates C' C² to extend over the crossing when the gates B' B² are lowered.

Each of the gates mentioned has combined with it a box E. In the present instance this 55 box is made in the form of a tubular lever and is pivoted midway between its ends at the axial line of the gate-pivot. As here shown, each box is provided with trunnions e' e², extending at opposite points from it and 60 midway between the ends. These trunnions fit in the standards B C, which support the gates.

The trunnions e² of the boxes extend through the gates with which the boxes are combined. 65 Nuts are shown as applied to the trunnions outside the standards. It will be seen that the gates and boxes are thus pivoted or fulcrumed between their ends to the standards without necessitating the employment of any 70 pivot-pins or fulcrums which pass through the boxes.

It will be seen that the rear ends of the beams forming the gates are provided with adjustable weights f. These weights are made 75 adjustable to enable a delicate poise of the gate-beams to be attained.

I have shown the gate-beams as made in two sections s' s². The sections s' are the main sections. The sections s² are hinged to 80 the main sections, so that they may be swung outwardly away from the adjacent track. Springs s³, attached to the main sections s' and impinging against the hinged sections s², press the latter into such position that they 85 will be in line with the main sections. This permits a person or an animal happening to be on the track at the time of the closing of the gates to push a portion of a gate outwardly and escape from an approaching 90 train.

Each box has a weight W. As shown, it is made in the form of a ball fitting snugly within the cylindric interior of the box and adapted to roll easily from one end of the box to the 95 other.

I have already shown that each box E is made in the form of a tubular lever. It remains to explain that each box is provided with two pins p' p². These pins extend to 100

ward the gate, with which the box co-operates. Each gate-lever is provided with a transverse extension or projection g . The pin p' of each box operates in conjunction with the upper surface of the rear portion of the gate-beam. I mean by the rear portion the portion which does not extend over the crossing when the gate is lowered. The pin p^2 of each box operates in conjunction with the projection g on the corresponding gate-beam. Whenever one of the boxes is tilted slightly its weight will roll to the depressed end, thereby tilting the box more. After it shall have tilted the box sufficiently one of the pins of the box will operate upon the adjacent gate-beam to tilt it. For instance, if a box E is tilted so that that end which is near the rear end of the opposite gate-beam shall be depressed, the weight of such box will roll down to the depressed end of the box, thus causing it to tilt further, and when the box shall have tilted far enough to bring its pin p' into contact with the upper surface of the rear portion of the gate-beam the further tilting of the box will cause a corresponding tilting of the gate-beam, and the forward end of the gate-lever—I mean the end extending over the crossing—will be raised. When the box is tilted in the reverse direction, its weight will run to the depressed end of the box, and the pin p^2 will operate upon the transverse extension g of the gate-beam so as to lower it. Obviously, to arrange the pins on each gate-beam instead of each box would 35 amount to a mere inversion.

I will now explain how each box E is tilted. It will be seen that near each end each box E is connected to a lever G , which is fulcrumed midway between its ends to the corresponding standard B . The connection is made by cords or chains $H' H^2$. These cords or chains are shown as fastened to lugs on the under side of the box E and extending through holes in the arms of the corresponding lever G , projections being provided at the ends of the said cords or chains to prevent them from being detached from the lever G . Lost motion is provided by these cords or chains.

Each lever G is connected by two cords, 50 chains, or like devices $I' I^2$ with tappets, which can be operated by a passing train. The cords or chains I^2 pass around guide-rollers i^2 to bell-crank or elbow levers J . These bell-crank or elbow levers J are connected by pins J' with levers $J^2 J^3$, forming tappets. These levers may be depressed by the cow-catcher T of a locomotive. When the tappet J^2 or J^3 is depressed, the train will be moving in the direction of the arrow, Fig. 2, and will 55 effect the oscillation of the lever J , and consequently of the corresponding lever G , in such direction as to effect the tilting of the corresponding box E in the same direction. This will merely start the tilting of the box E . The box E will afterward tilt slowly and as far as 60 permitted by the lost motion afforded by the

extra length of the cord H' , as compared with that length which would be necessary if it were desired to tilt the box E to the same degree, and only to the same degree, as the lever G . As the box E will tilt slowly, it will slowly lower the gate into the desired position to protect the crossing. The gate may thus be operated without endangering persons or things in the vicinity, and without jar, which 75 would be detrimental to itself.

The gate thus operated will remain lowered until the cow-catcher of the train reaches the tappets $K^2 K^3$. When the cow-catcher reaches this point, it will, by depressing the 80 tappets, lower the pin K' and oscillate the angle-lever K . This will effect a pull on the cord I' sufficient to effect the tilting of the lever G . The lever G will tilt the corresponding box E beyond the horizontal. After this the tilting of the box will continue, so as to slowly and easily effect the raising of the gate.

Each pair of gates has combined with it boxes E , chains or cords $H' H^2$, connected to the boxes, levers G , cords $I' I^2$, elbow-levers $J K$, pins $J' K'$, and tappets $J^2 J^3 K^2 K^3$.

The levers G for each pair of gates are secured upon a common shaft G' , that extends beneath the track. Owing to this the boxes 95 E for both gates of each pair may be oscillated by a single pair of cords or chains $I' I^2$ and the appurtenances thereof.

What I claim as my invention, and desire to secure by Letters Patent, is—

1. The combination, with a railway-gate having a transverse projection, of a lever and a movable weight supported by said lever, the said gate and lever being independently hung upon the same shaft, and the 105 said lever being provided with pins or projections for engaging the transverse projection and operating the gate, substantially as specified.

2. The combination, with a railway-gate having a rear extension and a transverse projection, of a lever independently hung upon the same shaft, a weight supported by said lever, pins or projections at opposite ends of said lever alternately engaging the rear extension and transverse projection of the gate, 110 tappets adjacent to the track, and connections between the tappets and said levers, substantially as specified.

3. The combination, with a railway-gate having a transverse projection, of a lever independently hung upon the same shaft, a weight supported by said lever, pins or projections engaging the transverse projection and rear portion of the gate, another lever 125 connected to the weight-supporting lever with provision for lost motion, tappets adjacent to the track, and connections between the tappets and the second-mentioned lever, substantially as specified.

4. The combination, with a gate B' , of a box E , provided with pins or projections for

operating said gate, a lever G, cords or chains H' H², cords or chains I' I², and tappets adjacent to the track, substantially as specified.

5. The combination, with a gate B', of a box E, provided with trunnions, on one of which the gate turns and is supported, said box containing a weight and having projec-

tions for operating a gate-beam, substantially as specified.
